CLAIM

The ornamental design for a spray head for a container, as shown.

DESCRIPTION

FIG. 1 is a front elevation view of a new design of a spray head for a container.

FIG. 2 is a left side elevation view thereof.

FIG. 3 is a right side elevation view thereof.

FIG. 4 is a top plan view thereof.

FIG. 5 is a bottom plan view thereof.

FIG. 6 is a top, front and left side perspective view thereof.

FIG. 7 is a bottom, rear and right side perspective view thereof.

FIG. 8 is a bottom, rear and left side perspective view thereof; and,

FIG. 9 is a top, front and right side perspective view thereof. The broken lines depict portions of the spray head that form no part of the claim.
